UNITED STATES PATENT OFFICE.

RICHARD H. WELLES, OF KENOSHA, WISCONSIN.

DESIGN FOR A HEADLIGHT.

No. 38,926.

Specification for Design.

Patented Dec. 3, 1907.

Application filed September 19, 1907. Serial No. 393,739. Term of patent 7 years.

To all whom it may concern:

Be it known that I, RICHARD H. WELLES, a citizen of the United States, residing at Kenosha, in the county of Kenosha and State of Wisconsin, have invented a new, original, and ornamental Design for Headlights, of which the following is a specification, reference being had to the accompanying drawing, forming part thereof, in which—

Figure 1 is a side elevation of a head-

light showing my new design, Fig. 2 is an end elevation of a head-light showing my new design.

I claim:

The ornamental design for a head-light as shown.

RICHARD H. WELLES.
